UNITED STATES PATENT OFFICE.

CHARLES HUNT, OF MANCHESTER, NEW HAMPSHIRE.

FRUIT-JAR COVER.

1,318,671.

Specification of Letters Patent.

Patented Oct. 14, 1919.

Application filed May 21, 1919. Serial No. 298,661.

To all whom it may concern:

Be it known that I, CHARLES HUNT, a citizen of the United States, residing at Manchester, in the county of Hillsborough and State of New Hampshire, have invented certain new and useful Improvements in Fruit-Jar Covers, of which the following is a specification, reference being had to the accompanying drawings.

10 This invention relates to an improved fruit jar closure and clamp therefor, and an object of the invention is to provide a closure, which is simple, efficient and practical in construction, and may be manufactured for relatively low cost and sold at a reasonable profit.

A further object of the invention is the provision of a closure and clamp therefor including an anchoring ring to engage 20 around the neck of the jar, and an arched metallic strap arching across the top of the closure and provided with detachable hook connections with the anchoring ring, and a screw threaded through the strap and contacting with a part of the top of the closure, whereby it may be forced tightly in position, there being a gasket carried by the closure engaging the marginal edge of the open end of the jar, so as to seal the jar 25 tight, when the closure is clamped in position.

The invention further aims to provide means on a part of the closure to be engaged by the end of the screw, to prevent 30 lateral displacement thereof.

The invention further aims to provide offset portions in the anchoring ring, to hold the detachable hook connections spaced from the neck.

40 The invention further aims to provide an anchoring ring having diametrically opposite eyes, to receive hooked ends of a twisted wire clamping member, which arches the closure, and which also carries a clamping 45 screw, for clamping the closure in place.

While the design and construction at present illustrated and set forth is deemed preferable, it is obvious that as a result of a reduction of the invention to a more practical form for commercial purposes, the invention may be susceptible to changes, and the right to these changes is claimed, pro-

vided they are comprehended within the scope of what is claimed.

The invention comprises further features 55 and combination of parts, as will be herein-after set forth, shown in the drawings and claimed.

In the drawings:

Figure 1 is a sectional view through the 60 upper part of the fruit jar, showing the improved closure and clamping means as applied thereto.

Fig. 2 is a detail view of the clamping arch, which is constructed of twisted wire. 65

Fig. 3 is a detail view of the anchoring ring, showing the diametrically opposite eyes to be engaged by the hooks of the arched clamping member.

Fig. 4 is a sectional view through the 70 upper open end of a fruit jar, showing another form of closure and clamping means as applied.

Fig. 5 is a detail perspective view of the 75 anchoring ring to be engaged by the clamping strap.

Fig. 6 is a detail perspective view of the clamping strap.

Referring more especially to the drawings, 1 designates the body of a fruit jar, having 80 a neck 2, and 3 denotes a closure, which is of a general shape as shown, but may be otherwise constructed, and is provided with an annular groove or channel 4, for the reception of the gasket or washer 5, which may 85 be constructed of any suitable material, preferably rubber or a composition of rubber and canvas. This gasket or washer is designed to engage the upper marginal edge of the open end of the jar, to insure a fluid 90 and air-tight seal between the closure and the jar.

An anchoring ring 6 is in surrounding relation to the neck of the jar, and this ring is constructed from a single length of wire 95 having its ends provided with interengaging hooks 7, to hold the ring in place on the neck. This ring is bent at diametrically opposite portions, to form eyes 8. A clamping arch member 9 is provided. This clamping 100 member is constructed from a single length of wire, which is twisted upon itself as illustrated, to insure strength and rigidity. However, when the wire of the clamp-

ing arch is twisted together, the opposite portions of the wire substantially centrally of the arch are bowed outwardly, as shown at 10, thereby providing an opening 11, which is threaded to receive the binding or clamping screw 12. The end portions of the clamping arch are bent to form hooks 13, which engage the diametrically opposite eyes of the anchoring ring. When closing the jar, the closure is applied in position, then the clamping arch is moved to arch the closure, after which the binding screw is adjusted, so that its extremity will engage a transverse groove 14 of an enlargement 15, which forms an integral part of the upper face of the closure. The closure is designed to be positioned, so that the transverse groove 14 is disposed in a plane parallel with the transverse disposition of the clamping arch, so as to prevent the clamping arch from swinging laterally, and consequently prevent the extremity of the screw from disengaging the groove of the enlargement of the closure. When the extremity of the screw is in contact with the transverse groove of the enlargement, the screw is tightened, thereby forcing the closure tightly into position, in order to insure a seal between the gasket or washer and the marginal edge 30 of the open end of the jar. The groove 14 not only prevents the clamping arch from swinging laterally, but also permits the closure to be moved laterally. In other words, before loosening the screw, the operator may apply pressure on the side of the closure, so as to rupture the connection or contact between the upper marginal edges of the jar opening and the gasket or washer 5, so that when the screw is loosened, the closure may be more readily removed from the jar. Furthermore, pressure may be applied upon the clamping arch, in a direction with the arch, that is longitudinally with the arch, so as to cause the end of the screw 45 to disengage the groove. In this case, the end of the screw will engage the top of the closure on one side of the enlargement, allowing the screw to be more easily loosened. These methods of removing the closure are 50 essential, in view of the fact that the screw may so firmly engage the closure, as to render it difficult to loosen the same, hence the provision of the groove, as heretofore stated.

55 In Figs. 4, 5 and 6, the anchoring ring, instead of having the eyes, is provided with diametrically opposite offset parts 16, which are engaged by the hooks 17 of the arched metallic strap 18. This metallic strap is more or less flexible, and its central portion receives a threaded shank of a clamping screw 19. In applying the closure shown in Figs. 4, 5 and 6, the closure is placed in position, then one end of the metallic strap is formed into the hook, and

placed in engagement with one of the offset portions of the anchoring ring. The other end of the strap is then inserted through the opposite offset portion, and bent upwardly as shown to provide the other hook 70 on the strap. The clamping screw is then tightened, with its end firmly engaging the groove and the enlargement of the upper face of the closure, and by tightening up the screw, and tensioning the strap, the 75 closure will be forced into position to insure a fluid and air-tight seal with the marginal edge of the upper open end of the jar, through the medium of the gasket or washer. When the screw is loosened and the clamping 80 arch member or wire 9 is removed, the cover can be easily taken off without the use of a knife or any other sharp instrument in between the closure and the marginal edge of the jar, or without submerging the jar into 85 hot water, for the purpose of softening the seal or the joint between the closure and the jar.

The invention having been set forth, what is claimed as new and useful is:

1. The combination with a fruit jar having a neck, of an anchoring ring in surrounding relation to the neck, a closure for the open end of the jar provided with an enlargement on its upper face, said enlargement having a groove, a clamping arched member arching the closure and having its opposite ends connected to the anchoring ring and provided with a centrally disposed threaded opening, said arching 95 member being disposed transversely of the closure in a plane parallel with the groove of the enlargement, and a screw in said threaded opening having its extremity 100 engaging said groove to clamp the closure 105 securely in position, said arching clamping member being constructed from a single length of wire twisted upon itself to insure strength and rigidity and having its opposite ends turned to form hooks, said connections between the clamping part and the anchoring ring comprising eyes on the anchoring ring to receive said hooks. 110

2. The combination with a fruit jar having a neck, of an anchoring ring in surrounding relation to the neck provided with diametrically opposite eyes, a closure for the open end of the jar provided with an upwardly extending central enlargement 115 provided on its face with a transversely disposed groove, a resilient clamping arched member arching the closure having its opposite ends detachably engaging said eyes, the central portion of the arch of said member having a threaded opening substantially 120 normally concentric with the center of the closure, said arching clamping member being disposed transversely of the closure in a plane parallel with the groove of the enlargement, and a screw engaging said 125 130

threaded opening and having its extremity engaging said groove to clamp the closure securely in position, said groove constituting means to permit either lateral movement of the closure or lateral movement of the resilient clamping arching member, before the screw is entirely loosened.

In testimony whereof I hereunto affix my signature in the presence of two witnesses.

CHARLES HUNT.
